Primary Examiner — Clare E Heflin(74) *Attorney, Agent, or Firm* — Beeson Skinner Beverly, LLP**CLAIM**

The ornamental design for a luminaire, as shown and described.

DESCRIPTION

FIG. 1 is a bottom front perspective view of a luminaire showing our new design;

FIG. 2 is a top rear perspective view thereof;

FIG. 3 is a left side elevational view thereof, the right side being a mirror image;

FIG. 4 is front elevational view thereof;

FIG. 5 is a rear elevational view thereof;

FIG. 6 is a top plan view thereof; and,

FIG. 7 is a bottom plan view thereof.

The broken line triangles shown at the foot of the luminaire in FIGS. 1 and 7 are boundary lines; the area within the boundary lines form no part of the claimed design.
